UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

CHAIN-STITCH SEWING-MACHINE.

1,107,659.

Specification of Letters Patent. Patented Aug. 18, 1914.

Application filed December 8, 1913. Serial No. 805,220.

To all whom it may concern:

Be it known that I, ALBERT H. DE VOE, citizen of the United States, residing at Westfield, in the county of Union and State 5 of New Jersey, have invented certain new and useful Improvements in Chain-Stitch Sewing-Machines, of which the following is a specification, reference being had therein to the accompanying drawings.

10 This invention has for its object to provide simple, effective and compact lower thread handling means for that class of machines constructed with a frame having the main or driving shaft journaled therein beneath the work-plate sufficiently above the 15 base to receive a balance-wheel exposed wholly above the supporting table for convenient grasp by the operator. In such class of machine it is important that the work-plate be arranged as near as possible to the 20 level of the supporting table, thereby making it difficult to employ looper mechanism of approved type and construction by reason of the limited height of the space between 25 the work-plate and the lower face of the machine base.

According to the present improvement, the main-shaft has fixed thereon the usual balance-wheel with attached belt-pulley and 30 carries also the actuating elements for imparting the requisite reciprocating movements to the needle and operative movements to the feeding mechanism, and the loop-taker shaft is journaled beneath and 35 connected with the main-shaft and has at its forward end a single inclined crank element operatively connected with and imparting operative movements to the looper which is mounted upon a rocking and endwise movable support having its axis of movement in substantially intersecting relation with that of the looper-actuating shaft.

In the preferred form of the improvement I make use of looper mechanism conforming 45 in general construction with that of my Patent No. 1,100,124, dated June 16, 1914. In order, however, to secure the requisite length of bearing between the sliding and pivotal connections to insure durability and 50 precision of looper movements, the inclined crank of the looper-actuating shaft is made tubular to afford an internal bearing extending lengthwise over the hub by which it is secured to the shaft, and the intermediate 55 rocking connection with the looper-carrier

is formed with a pin entering and having a length corresponding with said bearing. By this means, the inclined crank element is given a substantial and rigid connection with the shaft which it overhangs but 60 slightly and each of the sliding and pivotal connections has ample bearing area to give the best results.

According to the present improvement, the driving connection between the main and 65 looper-actuating shafts carries a minimum load, in that all parts excepting the looper are actuated directly from the main-shaft, the looper-actuating shaft being relieved even of the looper-thread take-up and nip- 70 piping devices which are operated by independent connections with the eccentric-rod through which motion is transmitted from the main-shaft to the needle-actuating rock-shaft. 75

In the accompanying drawings, Figure 1 is a side elevation of a sewing machine embodying the present improvements, and Fig. 2 a plan of the same with the bracket-arm removed. Fig. 3 is a transverse sectional elevation of the machine looking toward the bracket-arm standard. Fig. 4 is a detail perspective view of the looper and its actuating means. 80

The frame of the machine is shown constructed with the base 1 from which rises the standard 2 sustaining the lateral overhanging arm 3 terminating in the head 4. At its forward end the base is provided with the post 5 formed at its upper end with the 85 flat-topped enlargement 6, and intermediate the ends with a bearing member 7 having at the rearward end the extension 8 also provided with a flat top upon which and the top of the post 5 is secured the work-plate 9. 90

Journaled in the lower portion of the standard 2 and in the extension 8 slightly beneath the work-plate is the main-shaft 10 having fixed upon its rearward end the balance-wheel 11 with attached grooved pulleys 12 and needle-actuating eccentric 13; and adjacent the bearing member 8 it is provided with the feed-actuating and lifting eccentrics 14 and 15. 100

Journaled within the frame members 2 and 7 beneath the main-shaft is the rotary looper-actuating shaft 16 having an operative connection with the main-shaft through the intermeshing gears 17 and 18. Secured 105 upon the forward end of the main-shaft ad- 110

5 jacent the lateral boss 7' of the bearing member 7 by means of the clamp-screws 19 is the split hub 20 of the tubular crank element 21 having the axis of its cylindrical bore inclined to that of the actuating shaft 16.

10 To the bore of the crank element 21 is fitted the cylindrical pin 22 sustained by the upwardly projecting arm 23 of the split collar 24 having secured therein by means of the clamp-screw 25 the cylindrical pin 26 disposed crosswise of the pin 22 and extending oppositely across the end thereof. The pin 26 is fitted within the bore of the tubular looper-carrier 27 which is provided near its 15 lower end with the laterally projecting cylindrical pin 28 fitted to slide and oscillate within the aperture of the bearing boss 29 which is sustained by an extension of the post 5. The axis of the bearing boss 29 is 20 disposed in substantially intersecting relation with that of the main-shaft and slightly at one side of the axis of the tubular crank element 21. The looper-carrier 27 has near its upper end the lateral lug 30 formed with 25 a socket in which is secured by means of the set-screw 31 a stud depending from the shank 32 of the looper whose blade 33 has adjacent its point the thread delivery aperture 34 at one extremity of the longitudinal 30 thread-groove or channel 35 provided at the opposite end with a thread-eye 36 of suitable form.

35 The looper coöperates in the production of a double-chain-stitch seam with an eye-pointed needle 37 carried by the reciprocating needle-bar 38 which is journaled in the bracket-arm head 4 and connected by the link 39 with the crank-arm 40 upon the needle-actuating rock-shaft 41 journaled 40 upon the member 3 of the bracket-arm. The rock-shaft 41 has secured upon its opposite end the hub 42 of a crank-arm 43 connected by means of the screw-stud 44 with the upper end of the connecting rod 45 provided 45 at its opposite end with the split strap 46 embracing the actuating eccentric or crank element 13 of the main-shaft from which the needle derives its reciprocating movements.

50 The cap of the eccentric-strap 46 is provided with a lug 47 which affords a seat upon which is secured by means of the fastening screw 48 the foot 49 of the take-up arm 50, a similar arm 51 having its foot 52 secured adjustably upon the member 49 by 55 means of the fastening screw 53. The take-up arms 50 and 51 are provided with the cam-shaped thread-apertures 54 arranged in alinement, and are spaced apart to admit between them the stationary thread-arm 55 60 formed with the cam-shaped thread-slot 56 and having its shank 57 secured by means of the screw 58 upon a block 59 provided at opposite sides thereof with apertures in which are secured by screws 60 the shanks 65 of the depending rigid thread-arms 61 pro-

vided in their lower extremities with alined guide-apertures 62, the arms 61 being sufficiently separated to embrace the arms 50 and 51.

65 The bracket-arm sustains at the head of the standard 2 the needle-thread and looper-thread tension devices 63 and 64 provided respectively with the guide-washers 65 and 66 having the thread-apertures 65' and 66'. Upon the standard 2 intermediate the tension devices and the guide-arms 61 is secured by means of the screw 67 the transverse block 68 having fastened thereon by means of the screw 69 and steady pin 70 the normally separated superposed nipper-plates 71 and 72, the former being provided in its outer end with the notched guide-lips 73 to guide the thread between such plates. Journaled in a transverse aperture of the standard and the block 68 is the push-pin 74 having its head 75 countersunk beneath the inner nipper-plate 71, its opposite end projecting beyond the standard within the range of movement of the plate 76 which is formed with the flange 77 secured by the screw 78 upon one face of the connecting rod 45. The nipper-plates remain separated for the free passage of the thread through the notched guide-flanges 73 excepting during the rise of the connecting rod in its forward position, when the plate 76 presses the pin 74 forwardly and causes it to act upon the inner nipper-plate for temporarily gripping the thread between itself and the outer nipper-plate. As both of these plates are 100 formed of resilient material they effect a yielding engagement with the thread. The nipping pressure can obviously be regulated either by adjustment of the fastening screw 69 or by adjustment of the position of the plate 76 upon the connecting rod 45.

105 The feed-actuating eccentric 14 is embraced by the strap at one end of the eccentric rod 79 whose apertured opposite end embraces the stud 80 adjustably mounted upon the slotted arm 81 of the feed-rocker 82 mounted upon the fulcrum-bar 83 sustained by the frame. Fulcrumed upon the pivotal pin 84 of the feed-rocker is the frame 85 having a lateral arm 86 carrying the feed-dog 87 and a second arched arm 88 provided with the socket 89 in which is journaled the plunger-pin 90 having at its outer end the strap 91 embracing the feed-lifting eccentric 15. The work-advancing and rising and falling movements are imparted to the frame 85, and consequently to the feed-dog 87, by the connections with the main-shaft just described. Opposed to the feed-dog 87 is the usual presser-foot 92 secured to the presser-bar 93 which is journaled as usual in the head 4 of the bracket-arm.

110 In threading the machine, the needle-thread is led from the source of supply 130

through the guide-eye 65' between the component disks of the tension device 63 and thence through the usual guide members, including the usual guide-eye 94 upon the 5 needle-bar, to the needle. The looper-thread is passed through the guide-eye 66' and tension device 64 and thence between the nipper-plates, guided by the notched flanges 73, from which it is passed successively 10 through the rearward thread-arm 61 and the apertures of the take-up members 51 and 50 and through the eye of the second thread-arm from which it is led through an aperture in the extremity of the fixed guide-arm 15 95 to the heel of the looper-blade from the point of which latter it emerges.

In the stitching operation, the needle descends and presents its loop which is entered upon the rearward side by the looper as the 20 needle begins its rise, the advance of the looper to extreme position serving to draw the thread freely through the take-up device and through the separated members of the 25 nipping device to secure looper-thread through the tension device for the succeeding 30 stitch-forming operation. In the retrograde movement of the looper upon the opposite side of the needle subsequent to the feed of the work, the apertured take-up 35 members 50 and 51 receive the looper-thread into the depending extremities of their apertures and carry the intermediate portion of thread against the straight lower edge of the fixed member 55 in advance of the slot 56 so as to effectively take up the slack thread 40 given up by the retreating looper in order that the looper-thread may be taut when the point of the then descending needle encounters the strand leading from the looper point 45 to the work. As the looper continues to retreat and its point passes the needle-path, the take-up arms 50 and 51 draw the looper-thread within the slot 56 of the fixed member 55 which conforms in shape substantially 50 to their path of movement, thereby materially retarding the thread drawing action which continues at a reduced rate until the recession and descent of the arms 50 and 55 55 causes the stripping of the thread from the lower ends of the apertures 54 by action of the fixed member 55 about at the end of the retraction of the looper, when the take-up action entirely ceases and the looper-thread is slackened for the succeeding advance of the looper in the next stitch-forming cycle. The nipper remains open until about the time that the looper presents its thread for engagement of the needle at which time the 60 looper-thread is drawn taut by the take-up device, when the nipper becomes closed to insure against the stealing of an additional supply of thread through the tension device.

Heretofore it has been proposed to provide a rotary shaft with an inclined looper-actuating crank-pin having an external bear-

ing face which could be utilized only beyond its point of connection with the shaft, the coöperating member being apertured to embrace said crank-pin. In the type of sewing machine represented in the accompanying drawings, the employment of looper mechanism involving such an element has been found to be impracticable without the loss of certain desirable features before noted. By providing a tubular looper-actuating crank-pin having an internal bearing surface to receive a pin fitted within the same, the greatest compactness is secured with bearing surfaces of sufficient area to insure durability, quiet running and precision in the looper movements.

By the provision of an auxiliary shaft for actuating the looper, this element of the construction has been so arranged, not only to permit the employment of the inclined looper-actuating crank element, but to accommodate coöperating elements so proportioned and arranged as to adapt to this type of machine the constructive features of special importance characteristic of the looper mechanism forming the subject of my aforesaid Patent No. 1,100,124.

Heretofore it has been customary to actuate all the lower thread handling devices by direct connections with the looper-actuating shaft, but according to the present improvement the auxiliary shaft performing such function is entirely relieved of the take-up and nipper-operating means, thereby lightening the load upon the looper-actuating shaft and thus reducing the liability to noise through the operation of the connecting gears at the high rate of speed at which the present mechanism is designed to operate.

In certain aspects of the present improvement it is immaterial which member of the looper mechanism is formed with the tubular element entered by the coacting turning and endwise movable element, and this is to be understood in connection with the recital of such elements in certain of the appended claims.

Having thus set forth the nature of the invention, what I claim herein is:—

1. In a sewing machine, the combination with the frame comprising a base and a bracket-arm rising therefrom and a work-plate sustained above the base, of a main-shaft journaled in said frame below the work-plate and provided with a balance-wheel disposed above the lower face of said base, a reciprocating needle operatively connected with said main-shaft, feeding mechanism also operatively connected with said main-shaft, a looper-actuating shaft mounted in said frame between the main-shaft and the lower face of said base, a driving connection between said shafts, an inclined crank upon the forward extremity of said

- looper-actuating shaft, a looper coöperating with said needle and adapted for oscillation and endwise movement upon an axis in substantially intersecting relation with that of 5 said actuating shaft, and an operative connection between said looper and crank including a pin fitted to said crank and adapted for turning and endwise movement relatively thereto.
- 10 2. In a sewing machine, the combination with the frame comprising a base and a bracket-arm rising therefrom and a work-plate sustained above the base, of a reciprocating needle, an actuating shaft journaled 15 in said frame below the work-plate and provided at its forward extremity with an inclined tubular crank having its axis in substantially intersecting relation with that of 20 said shaft, a looper coöperating with said needle and adapted for oscillation and endwise movement upon an axis in substantially intersecting relation with that of said actuating shaft, and an operative connection 25 between said looper and crank including a pin fitted revolvably within the bore of said tubular crank.
3. In a sewing machine, the combination with the frame comprising a base and a bracket-arm rising therefrom and a work-plate 30 sustained above the base, of a main-shaft journaled in said frame below the work-plate and provided with a balance-wheel disposed wholly above the lower face of said base, a reciprocating needle, feed-actuating and needle-actuating elements carried by said main-shaft, feeding mechanism operatively connected with the feed-actuating elements, means including a connecting-rod formed with a strap embracing the needle-actuating element for imparting operative movements to the needle, an endwise and sidewise movable thread-carrying looper, a looper-actuating shaft mounted in 35 said frame beneath the main-shaft with which it is operatively connected, a crank and sliding-pin connection between said looper-actuating shaft and the looper and looper-thread take-up and nipping devices each including an operative element mounted upon said connecting-rod.
- 40 In testimony whereof, I have signed my name to this specification, in the presence of two subscribing witnesses.
- ALBERT H. DE VOE.
